NILS H. ANDERSON, OF MIDDLETOWN, CONNECTICUT, ASSIGNOR TO THE NOISELESS TYPEWRITER COMPANY, OF MIDDLETOWN, CONNECTICUT, A CORPORATION OF CONNECTICUT.

TYPE-WRITING MACHINE.

1,255,570.

Specification of Letters Patent. Patented Feb. 5, 1918.

Application filed October 11, 1913. Serial No. 794,595.

To all whom it may concern:

Be it known that I, NILS H. ANDERSON, a citizen of the United States, residing at Middletown, in the county of Middlesex and 5 State of Connecticut, have invented certain new and useful Improvements in Type-Writing Machines, of which the following is a full, clear, and exact description, such as will enable others skilled in the art to which 10 it appertains to make and use the same.

This invention relates to typewriting machines and with regard to certain more specific features thereof, to carriage shifting mechanism and associated and coacting parts.

One of the objects of the present invention is to provide a carriage shifting mechanism which will be simple and practical in its construction and durable and efficient in 20 action. Another object is to provide a carriage shifting mechanism of the above character which will be particularly applicable to silently operating machines. A further object is to provide practical means for so 25 mounting the parts as to permit various adjustments thereof as may be necessary, as well as to enhance their ease of movement and reduce the wear on such parts. Other objects will be in part obvious and in part 30 pointed out hereinafter.

The invention accordingly consists in the features of construction, combinations of elements and arrangements of parts which will be exemplified in the construction hereinafter set forth, and the scope of the application which will be indicated in the following claims.

In the accompanying drawings wherein is shown one of the various possible embodiments of this invention,

Figure 1 is a plan view of the complete carriage shifting mechanism and such associated and coacting parts as are necessary to understand the present invention;

45 Fig. 2 is a sectional elevation of the shift mechanism in normal or inactive position;

Fig. 3 is a similar view with parts shown in shifted position for printing upper-case characters, such as capital letters;

50 Fig. 4 is a similar view showing the parts in shifted position for printing lower-case characters or figures;

Fig. 5 is a detail sectional view taken on the line s—s, Fig. 4;

Fig. 6 is a detail view showing the means 55 for limiting the movement of a shifted part; and

Fig. 7 is an enlarged detail view, partly in section, showing the mounting of one end of the shift rock shaft. 60

Similar reference characters refer to similar parts throughout the several views of the drawings.

The present invention will be hereinafter described with relation to a Noiseless type-writing machine, to the application of which it is particularly designed, although it is to be understood that various features of the present invention are equally applicable to other forms of typewriting machines. 70

The Noiseless typewriting machine, as is well known, comprises a longitudinal reciprocating carriage traveling along a horizontally disposed shift rail positioned in the upper rear part of the machine. Radially 75 disposed pressure-operated type carriers each carrying three characters or type are adapted to coact with paper carried by the platen at each operation of suitable finger-actuated keys mounted in the keyboard of 80 the machine. The carriage is adapted to be shifted upward or downward from a normal intermediate position wherein it receives the small or lower case characters.

These parts and mechanisms, with the exception of the shift mechanism forming the subject of the present invention, are all, broadly speaking, of such well-known general character and function as not to require illustration and a detailed description 85 thereof, as they form no part of the present invention except in so far as certain of these features may enter broadly into the combinations hereinafter claimed.

Referring now to the drawings in detail, 95 and more particularly to Figs. 1 and 2, the carriage above mentioned is adapted to travel along a suitable shift rail 1 which is moved upward or downward as the mechanism is operated to assume positions shown 100 in Figs. 3 and 4 respectively, by means of the capital shift key 2 or the figure shift key 3 shown at the side of the machine adjacent the letter keys of the key-board. The figure

- shift key lever 4 is pivoted upon a bracket 5 at the point 6 which is secured to a portion of a transverse support or brace 7 of the machine, while the capital shift key lever 8 is pivoted at 10 upon the same support immediately therebelow. The rear ends of the shift key levers 4 and 8 cross each other and are each pivotally connected at 12 and 11 to floating links 14 and 13 respectively.
- 10 The opposite ends of these links are in turn pivotally connected at 15 and 16 to a floating lever or rocking member 17. This rocking member 17 is pivotally supported at 18 in a yoke 20 pivotally mounted at 21 between forwardly extending ears of a bracket 22. The rocking member 17 has three arms, the two shorter of which are connected to the floating links 13 and 14, while the rearwardly extending longer arm is pivotally connected at the point 23 to a vertically disposed link 24, the opposite end of the link being pivotally connected at 25 to an arm 26 secured to a main shift rock shaft 27. This rock shaft also carries near its ends, arms 28 and 30 as more clearly shown in Fig. 1, each arm being provided at its rear end with trunnion blocks 31 adjustably secured to the lower end of vertically disposed connecting members or links 32 supporting the end of 30 the shift rail 1 upon which the carriage travels.
- In shifting the carriage downward into a position for printing figures as shown in Fig. 4, the shift key lever 4 is depressed and rocks about the pivotal connection 5 on the bracket 7 upon which it is supported into the position shown. It is evident that the distance from the centers 6 and 16 tends to shorten, consequently the long or rearwardly extending arm of the rocking member 17 is rocked downward, causing the yoke 20 to be moved toward the center 6 about which the shift key turns. This downward movement of the rocking member transmits a rotary motion to the main rock shaft 27 through the vertically disposed link 24 connected at its lower end to the rear end of the intervening arm 26. This rock shaft in turn transmits motion to the vertically disposed links 32 and the shift rail along which the carriage travels, thus bringing the carriage downward in a proper printing position for receiving the lower bank of characters, or figures.
- 45 The capital shift key lever 8 plays an important part during the operation of the figure shift key lever, for the centers 10, 11 and 15 in the train of mechanism to the rocking member 17 will be in a straight line 50 and held against deflection or overthrow by an adjustable padded stop 33 acting on one side and the coil spring 34 acting upon the other, as shown in Fig. 1. In practice it may be desirable to bring these pivotal cen-

ters or points slightly out of alignment, the 65 middle pivot 11 being lower than the others so that when the figure shift key lever is depressed the capital shift key lever through the short floating link 13 will hold the upper end of this rocking member 17 in relatively fixed position or against forward movement thereof, thus insuring the desired movement to the rocking member.

70 The capital shift key lever 8 and intermediate mechanism operates in substantially the reverse manner in order to rock the rocking member 17 upward to rotate the main shift rock shaft 27 and connecting arms 28 and 30 in the opposite direction to raise the vertically disposed connecting links 80 32 and move the carriage into proper printing position for receiving the capital letters, as clearly shown in Fig. 3 of the drawings.

75 The figure shift key lever is also arrested in normal position by an adjustable padded stop 35 and is held in contact with this stop by a vertically disposed coil spring 36 which aids in the return of the parts to normal position.

80 The present machine is provided with two 90 capital keys, one at each side of the keyboard and a figure key upon one side in order to assist the operator when operating under the touch system.

In order that the depression of either 95 capital key may produce the desired results, a rock shaft 40 is mounted in suitable brackets 41 projecting forwardly from the central transverse support 7 as shown in Figs. 1 and 2. At one end of this shaft 40 is fastened a key lever 42 held against rotation thereon in any well-known manner, such for example, as an irregular shaped hub nut 43 as indicated. To the opposite end of the shaft is secured a downwardly extending 100 arm 44 pivotally connected at its lower end to a link 45 having in its opposite end an opening or slot 46 engaging a stud 47 on the end of an arm 48 projecting downwardly from the capital shift key lever 8, which 105 will cause this shift key lever to rotate on its pivot 10 and operate the shifting mechanism in the manner above described. This auxiliary key lever 42 is returned to its normal position by a spring 50 coiled about the 110 auxiliary rock shaft 40 having one end resting against the stationary part of the frame of the machine and the opposite end secured to an adjustable collar 51 rotatively mounted upon the shaft, thus furnishing a means 115 by which the necessary tension of the spring may be obtained in order to hold the auxiliary shift key lever in its normal position. When the capital shift key 2 at the opposite side of the keyboard is operated it is 120 permitted to have an independent movement by reason of the stud and slot connection 46-47 above described, in which the stud

simply slides in the slot without in any way affecting the position of the auxiliary shift key at the right of the keyboard. An adjustably mounted padded stop 52 is secured 5 in proper position on the turned over end 53 of connecting link 45 to arrest the return movement of the auxiliary shifting key in a silent manner.

To the upper end of the yoke supporting 10 the rocking member is connected a coiled tension spring 54, the opposite end of which is secured to an adjustable support provided with an automatic, or self-locking adjusting nut 56, supported from a stationary bracket 57. This spring 54 serves to aid in the return of the shifting mechanism to normal position from either of the shifted positions, it being understood that the yoke 20 shifts toward the main pivots of 15 the shift key levers when actuated. As the movement of the yoke in either case is slight, it forms a very desirable part to attach the return spring,—in fact, by so attaching the spring an overloading of the stroke of either 20 shift key at the end thereof, is prevented. The springs 34 and 36 above referred to 25 connected with the shift key levers adjacent their pivoted supports, also serve to return the shift key levers to normal position. The primary 30 object of these latter springs is, however, to maintain the centers of one toggle formed by the key levers and intervening floating links in normal position when operating the other shift key as previously 35 described. In order to reduce the strain centered upon these return springs as much as possible, the carriage is balanced to a 40 certain extent by spiral balance springs 60 as shown in Fig. 1. The inner ends of these springs are connected to an adjustable collar 61 adapted to be actuated by a worm and gear mechanism 62, the outer ends being attached to the frame of the machine.

When printing a list of numbers or a 45 sentence entirely in capital letters, for example, it is sometimes desirable to hold the carriage in shifted position for a relatively long period of time. In order to accomplish this without the necessity of the operator using one hand to hold down one of the shift key levers, auxiliary locking levers 50 63 and 64 are pivotally mounted upon the figure and capital shift key levers respectively. These auxiliary locking levers are 55 provided at their lower ends with hook portions 65 adapted to engage sheet-metal stops, or brackets 66, attached to any convenient portion of the frame of the machine. The locking levers, 63 and 64, are 60 also supplied with springs about their pivots 67 which will normally disengage or unhook the lower end 65 of the levers from their coacting stops. The locking levers are held in their locking position by the upward

pull exerted thereon by the return springs 65 34 and 36 of the shifting levers so that in order to unlock either lever 63 or 64 it is only necessary to depress the body portion of the respective shift key lever, thereby permitting the return springs of the locking levers to act immediately and withdraw the hook portions from the coacting stops.

It will also be noted from the above that the entire shift mechanism is so arranged that should the capital shift key lever be 75 locked, as shown in Fig. 3, for example, it can be released by pressing the figure shift key. This is due to the fact that the centers 10, 11 and 15 of the toggle formed by the capital shift key lever and link are not in 80 line, and by depressing the figure shift key lever in which the centers are in a straight line, it will tend to rock the yoke 20 toward the center of the shift key lever and force the capital shift key lever downward 85 in the same manner as the operator would naturally force the lever downward in attempting to unlock the capital shift lever. This result is obtained by reason of the fact that the momentum is transmitted 90 to point 15 and connected links and moves them prior to transmitting an effective movement to a more remote part of the mechanism. This is also reversed in the case of the figure shift lever being locked down, 95 as shown in Fig. 4. It can be unlocked by pressure on the capital shift key lever as above described. To further assist and insure the return of the capital shift lever from locked position when figure shift key 100 lever is depressed, an arm 70, as shown clearly in Fig. 3, extending rearwardly from the yoke, carries at its rear end an adjusting screw 71 made to engage while either shift is being operated, a portion 72 105 of the transverse support, but to clear this portion by perhaps a hundredth of an inch when in locked position. This very slight lost motion is sufficient to permit the movement above described, to unlock one shift 110 by depressing the other. Thus, when either of the shift levers is operated the yoke 20 is rocked forward causing the arm 70 and set screw 71 to come into contact with the stationary portion of the machine, thereby 115 preventing further rocking or tilting of the yoke.

It will be seen from Figs. 3 and 4 that with the capital shift key lever 8 in the position shown in Fig. 3 and the yoke being 120 rocked until the screw carried by the rearwardly extending arm is in contact with the abutment, it would require further rocking of the yoke in order to depress the figure shift key lever 4. This rocking, as above 125 stated, being prevented, it is evident that if the capital shift key lever 8 is in its lowest position as shown in Fig. 3 and not pre-

vented from returning to normal position by means of the auxiliary locking lever, pressure upon the figure shift key lever 4 will cause the rocking member 17 to rotate, 5 thus tending to straighten the toggle formed by the capital shift key lever and floating connecting link 13 and consequently will return this part of the mechanism to normal position and shift the carriage to a 10 position for printing figures. Should there be no return spring on this mechanism to return the carriage to its normal position, it would be possible by placing the fingers on both shift key levers to alternately press 15 them, thus moving the carriage directly from lower keys to upper keys.

For typewriting machines of the Noiseless character, or machines employing three type to each type carrier, it becomes necessary 20 to accurately register or stop the carriage in the three different printing positions. The means for registering the carriage in its central position is embodied directly in the shift mechanism structure, and attention 25 is directed particularly to Fig. 2 of the drawings in which it will be seen that the rocking member 17 forms one end for toggles composed of the shift key levers and connecting links. The shift key levers 30 are secured to a stationary bracket and it will, therefore, be seen that the rocking member cannot be rotated by any force applied to the long arm of this member. The toggles in extended position, therefore, form 35 a stop mechanism for the carriage in central position for printing small or lower case characters. The springs 34 and 36 serve to hold the centers of the toggles in alinement, thereby preventing vibration or 40 rebound of the carriage common in many shift mechanisms of other makes.

For accurately registering the carriage in upper and lower position, attention is directed to detail view, Fig. 6. In this structure 45 one of the connecting links 32 supporting the carriage shift rail carries an arm 73 securely held in adjusted positions by upper and lower check nuts 74. At the extreme end of this arm are oppositely disposed 50 truncated conical members 75 free to move sidewise a trifle, and also to rock slightly on this member. Secured in a bracket 76 or other relatively fixed part of the frame, is a threaded stud 77 having secured thereon two 55 arms 78 as shown. These arms are adjustably positioned in a vertical direction through adjusting and check nuts 80, as shown, and are provided at their outer ends with pockets 81 into which the conical members 75 carried 60 by the arm 73 are adapted to pass and fit, thus arresting the up-and-down movement of the link 32 and the vertical movement of the carriage supported thereby. It is, of course, to be understood that only one conical member 75 contacts with one pocket at a time 65

at the extreme end of the movement. By having these stops tapered or of cone shape, the contact will be made at the sides of the cone rather than on the truncated bottom or end portion, for it will readily be seen that a 70 contact on the bottom would not be sufficiently noiseless in its operation. The adjustment of the arms and cones carried thereby, is accomplished by raising and lowering the same on the link 32, in order to 75 bring the relation of the capitals and figures in correct alinement with the small letters by the combination of adjustments secured by the elements named. The slight freedom between the cones and the arm upon which 80 they are carried, is desirable inasmuch as it would be a difficult matter to secure an alinement between the pockets and the cones which would insure an accurate register.

The pivotal bearings and pivotal connections associated with this shifting mechanism have been developed with the view of securing a pivot which would be perfectly free to rotate and still have no side or lateral movement to cause inaccuracies in the 90 shifting of the carriage. In Fig. 5 of the drawings there are shown several forms of pivots and pivotal connections used for links throughout this structure. The central pivot 18 is in the form of a stud having a long 95 conical head 83 on one end, the opposite end being threaded to receive a conical nut 84 of the same taper as the head. The holes in the yoke 20 carrying the rocking member 17 are, of course, tapered and reamed to fit the 10 conical head and nut of the stud upon which the rocking member is adapted to turn. The portion of this screw and nut which project inside of the yoke or between the arms thereof, carries a rocking member, the hub of 10 the rocking member having been reamed to fit on the portion of the conical head of the screw and nut. The yoke which is made of more or less flexible material, is, before being assembled, somewhat wider than shown 11 in Fig. 5. The conical nut after passing through the rocking member is tightened to draw the arms toward each other until a tight fit is secured in the hub of the rocking member. This makes a very substantial and free working pivot, and when the desired adjustment is secured it is locked by an outside check nut 85 which is also assembled on the threaded portion of the screw stud 18.

The pivotal connection at the lower part 12 of the figure comprises the screw 21 and an opposite pivot point 86, this being the connection between the yoke and the bracket 22 supporting it. The yoke is provided with depressions, or holes, into which the points 12 fit.

The problem of securing the pivotal connections between the shifting levers 4 and 8 and the rocking member 17 is important 13 as these connections must be absolutely free

and yet have an accurate fit, for it is upon these studs that the proper intermediate alignment of the carriage depends. This pivotal connection is shown at the top of Fig. 5 and comprises a screw 15 having a taper portion close to its hexagonal head, the taper being approximately 10 degrees on the side. The end portion of the connecting link 18 is provided with a hole or opening reamed to fit the tapered portion of the screw. This form of pivotal connection can be adjusted to any desired nicety and checked by means of a nut 87 on the opposite side.

In Fig. 7 there is shown an enlarged view of the end mounting of the main shift rock shaft 27. The end of the rock shaft is provided with a reduced portion 90 and a ball raceway 91 coacting with a cup-shaped ball container 92 threaded into a side bracket 93 of the frame and held in adjusted position by means of a check nut 94 engaging the bracket. An annular ring 95 surrounds the ball retainer 92 flanged over on its opposite or inner side to protect the bearings 96 from dust and dirt.

It is believed that from the above description the method of use of this shifting mechanism is perfectly clear, and a further detailed description thereof is unnecessary. The device is simple and practical in its operation, is cheap to manufacture and assemble, and is believed to accomplish, among others, all of the objects and advantages above set forth.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In a typewriting machine, in combination, a carriage shift rail having a normal intermediate position, shift keys for moving the rail in opposite directions, and trains of connections between the keys and rail, including a floating lever common to the trains of connections and floating links intermediate the lever and said shift keys.

2. In a typewriting machine, in combination, a carriage shift rail having a normal intermediate position, shift keys for moving the rail in opposite directions, and trains of connections between the keys and rail, including a floating lever common to the trains of connection and floating links intermediate the lever and said shift keys, said floating links forming with the shift

key levers a pair of toggles adapted to lie

substantially in extended position when said rail is in said intermediate position.

3. In a typewriting machine, in combination, a carriage shift rail having a normal intermediate position, shift keys for moving the rail in opposite directions, and connections between the keys and rail, including shift key levers, a floating link at the end of each of said levers and a floating lever to which said links are connected, said shift levers crossing each other to obtain a better leverage on said floating lever.

4. In a typewriting machine, in combination, a carriage shift rail having a normal intermediate position, shift keys for moving the rail in opposite directions, and connections between the keys and rail, including crossed shift key levers pivoted to different parts of a fixed support, floating links forming extensions to said shift levers, a floating lever to which the ends of said links are connected and a connection between said floating lever and said shift rail.

5. In a typewriting machine, in combination, a carriage shift rail having a normal intermediate position, shift keys for moving the rail in opposite directions, and connections between the keys and rail, including shift key levers and floating links forming a pair of toggles occupying a normally extended position, one of said toggles adapted to act as a brace when the other of said toggles is flexed to shift the shift rail.

6. In a typewriting machine, in combination, a shift rail, a shift shaft, a floating lever connected with said shaft, floating links connected with different parts of said lever, and shift key levers connected to said floating links for actuating said levers, said links and shift levers forming toggles normally occupying extended position.

7. In a typewriting machine, in combination, a shift rail, a shift shaft, a floating lever connected with said shaft, floating links connected with different parts of said lever, shift key levers connected to said floating links for actuating said links, said links and shift levers forming toggles occupying a normally extended position, and means adapted to prevent an overthrow of said toggles whereby one toggle acts as a brace when the other toggle is flexed in moving the shift rail.

8. In a typewriting machine, in combination, a shift rail, a shift shaft, a floating lever connected with said shaft, floating links connected with different parts of said lever, shift key levers connected to said floating links for actuating said lever, said links and shift levers forming toggles occupying a normally extended position, and return springs connected with said shift levers adapted to hold the same in normal position.

9. In a typewriting machine, in combina-

- tion, a shift rail, a rock shaft supporting said shift rail, a floating lever connected with said rock shaft and means adapted to move said lever bodily forward to rotate the rock shaft in either direction.
- 5 10. In a typewriting machine, in combination, a shift rail, shift keys adapted to move said rail in opposite direction from a normal intermediate position, connections between the rail and keys comprising shift key levers and links connected therewith forming toggles occupying a normally extended position, one of said toggles adapted to be flexed when the connecting key is depressed, while the other acts as a brace, and means for returning the depressed key to normal position when the other key is actuated.
- 10 15 20 25 30 35 40 45 50 55 60 65 70 75 80 85 90 95 100 105 110 115 120 125 130
11. In a typewriting machine, in combination, a shift rail adapted to be moved in opposite directions from a normal intermediate position, a support for said rail, an arm carried by said support, two relatively movable members carried by said arm, two recessed members spaced apart adapted to be engaged by said members when the shift rail is shifted for silently arresting the movement of the shift rail, and means for adjusting the position of said recessed members.
12. In a typewriting machine, in combination, a shift rail adapted to be moved in opposite direction from a normal intermediate position, a support for said rail, an arm carried by said support, two conical members carried by said arm, two recessed members spaced apart adapted to be engaged by said conical members when the shift rail is shifted for silently arresting the movement of the shift rail, and means for independently adjusting the recessed members.
13. In a typewriting machine, in combination, a shift rail adapted to be shifted in opposite direction from a normal intermediate position, shift key levers, locking keys carried by said shift key levers for locking the shift rail in shifted position, and means for releasing the shift key lock by depressing the other shift key lever.
14. In a typewriting machine, in combination, a shift rail adapted to be shifted in opposite direction from a normal intermediate position, shift key levers in the keyboard of the machine, locking keys carried by said shift key levers adapted to lock the shift rail in shifted position, and operative connecting means between the opposite ends of said shift key levers whereby the locked shift key lever is released on depression of the other shift key lever.
15. In a typewriting machine, in combination, a shift rail adapted to be shifted in opposite direction from a normal intermediate position, shift key levers in the keyboard
- of the machine, locking keys carried by said shift key levers adapted to lock the shift rail in shifted position, and a connection between the opposite ends of said shift key levers whereby the locked shift key lever is released on depression of the other shift key lever, said connections comprising a floating lever and floating links intermediate the lever and said shift key levers.
16. In a typewriting machine, in combination, a shift rail adapted to be shifted in opposite direction from a normal intermediate position, shift key levers in the keyboard of the machine, locking keys carried by said shift key levers adapted to lock the shift rail in shifted position, and a connection between the opposite ends of said shift key levers whereby the locked shift key lever is released on depression of the other shift key lever, said connections comprising a floating lever and floating links intermediate the lever and said shift key levers, one of said floating links and the lever to which it is connected, forming a toggle occupying an extended position whereby pressure applied to the shift key lever connected therewith, will tend to further flex the toggle formed by the other floating link and shift key lever.
17. In a typewriting machine, in combination, a shift rail, shift key levers on one side of the keyboard for moving the shift rail in opposite direction from a normal intermediate position, an auxiliary shift key lever on the opposite side of the keyboard connected with said shifting mechanism for shifting the shift rail in one direction only, the connection between the said auxiliary shift key and shift rail comprising a bell crank lever, a link connected therewith, and a lost-motion device between said auxiliary shift key and the corresponding shift key at the opposite side of the keyboard whereby one may be operated independently of the other.
18. In a typewriting machine, in combination, a shift rail, shift key levers on one side of the keyboard for moving the shift rail in opposite direction from a normal intermediate position, an auxiliary shift key lever on the opposite side of the keyboard connected with said shifting mechanism for shifting the shift rail in one direction only, the connection between the said auxiliary shift key and shift rail comprising a bell crank lever, a link connected therewith, and a lost-motion device between said auxiliary shift key and the corresponding shift key at the opposite side of the keyboard whereby one may be operated independently of the other, said lost-motion device comprising a pin and slot connection.
19. In a typewriting machine, in combination, a shift rail adapted to be shifted in opposite direction from a normal intermediate position, shift key levers in the keyboard

- diate position, shift key levers at one side of the keyboard for controlling said movement, an auxiliary shift key at the opposite side of the keyboard for shifting the shift rail in one direction only, a rock shaft upon which said auxiliary shift key is mounted, and an adjustably mounted spring connected with said rock shaft for holding the same in normal position.
20. In a typewriting machine, in combination, a shift rail adapted to be shifted in opposite direction from a normal intermediate position, shift key levers at one side of the keyboard for controlling said movement, an auxiliary shift key at the opposite side of the keyboard for shifting the shift rail in one direction, a rock shaft upon which said auxiliary shift key is mounted, and an adjustable stop connected with said auxiliary key adapted to determine its initial position and silently arrest its return to said position after being depressed.
21. In a typewriting machine, in combination, a shift rail, a shift key in the keyboard of the machine, an intervening rock shaft connected with both of said parts, ball bearings supporting the ends of said rock shaft, an adjustable ball raceway for said bearings movable in the direction of the length of the rock shaft, and a housing for said bearings surrounding said raceway.
22. In a typewriting machine, in combination, a carriage having a normal intermediate position, shift keys for moving the carriage in opposite directions, connections between the keys and carriage including two toggles extended in said normal position, means whereby said carriage may be locked in shifted position, said elements being constructed and arranged so that upon actuation of one of said shift keys the carriage may be moved directly from a locked position of shift on one side of said intermediate position to a position of shift on the other side thereof.
23. In a typewriting machine, in combination, a carriage having a normal intermediate position, shift keys for moving the carriage in opposite directions, connections between the keys and carriage including two toggles extended in said normal position, a plurality of stops having coöperative inclined surfaces adapted to arrest the movement of the carriage in shifted position, means whereby said carriage may be locked in shifted position, said elements being con-
- structed and arranged so that upon actuation of one of said shift keys the carriage may be moved directly from a locked position of shift on one side of said intermediate position to a position of shift on the other side thereof.
24. In a typewriting machine, the combination with a shiftable part having three printing positions, of two toggles, a lever connected with the free ends of said toggles, means including a key for breaking one of said toggles to shift said part to one of said positions, means including another key for breaking the other of said toggles to shift said part to another of said positions, and locking means for each of said keys to hold said part in shifted position, said toggles and lever being so constructed and arranged as to permit release of either of said locking means by actuation of the other key.
25. In a typewriting machine, the combination with a shiftable part having three printing positions and shift key levers, of a triangular floating lever at the rear of the machine having one apex connected with said part and its other apices disposed in a substantially vertical plane and connected with said shift key levers.
26. In a typewriting machine, in combination, a part shiftable to different case positions, a pair of shift key levers extending along the base of the machine, and means including a lever at the rear of the machine beneath said part and having a movably supported axis, said lever being connected with said key levers and with said part for shifting the latter.
27. In a typewriting machine, the combination of a shiftable part having three printing positions, of two separate toggles which when both of them are extended hold said part in a middle position, means for breaking said toggles to move said part to its extreme positions, and locking means associated with said last-mentioned means to retain said part in extreme positions, said elements being so constructed and arranged as to permit release of said locking means by actuation of the means to move said part to opposite extreme position.

In testimony whereof I affix my signature, in the presence of two witnesses.

NILS H. ANDERSON.
